Primary Examiner — Robin V Webster(74) *Attorney, Agent, or Firm* — Raymond Y. Chan;
David and Raymond Patent Firm(57) **CLAIM**

The ornamental design for a sprinkler, as shown and described.

DESCRIPTION

FIG. 1 is a front view of an sprinkler showing my new design.

FIG. 2 is a rear view thereof.

FIG. 3 is a left view thereof.

FIG. 4 is a right view thereof.

FIG. 5 is a top view thereof.

FIG. 6 is a bottom view thereof; and,

FIG. 7 is a perspective view thereof.

The broken line in the drawing is included for the purpose of illustrating environmental detail and forms no part of the claimed design.
